US0D1053025S

(12) **United States Design Patent** (10) Patent No.: **US D1,053,025 S**
(45) Date of Patent: ** Dec. 3, 2024

(54) **WATCH**

(71) Applicant: **Chrono Star International Participations Groupe Franck Muller GmbH**, Stans (CH)

(72) Inventor: **Patrick Perez**, Genthod (CH)

(**) Term: **15 Years**

(21) Appl. No.: **35/519,487**

(22) Filed: **Dec. 8, 2023**

(80) **Hague Agreement Data**

Int. Filing Date: **Dec. 8, 2023**

Int. Reg. No.: **DM/233867**

Int. Reg. Date: **Dec. 8, 2023**

Int. Reg. Pub. Date: **Dec. 22, 2023**

(30) **Foreign Application Priority Data**

Jun. 22, 2023 (CH) 147463

(51) **LOC (14) Cl.** **10-02**

(52) **U.S. Cl.** **D10/39**
USPC .....
